UNITED STATES PATENT OFFICE.

ELMER W. TOWNE, OF NEW YORK, N. Y.

DESIGN FOR A SKIRT-BAND.

SPECIFICATION forming part of Design No. 28,246, dated February 1, 1898.

Application filed November 5, 1897. Serial No. 657,570. Term of patent 7 years.

To all whom it may concern:

Be it known that I, ELMER W. TOWNE, a citizen of the United States, residing at New York city, in the county and State of New York, 5 have invented and produced a new and original Design for a Skirt-Band, of which the following is a specification, reference being had to the accompanying drawing, forming a part thereof, in which is shown a perspective view 10 of a skirt-band embodying the features of my design.

The design consists in an ornamental band in which bars arranged in circumferentially-disposed groups A meet a series of transverse bars B.
